UNITED STATES PATENT OFFICE.

STANLEY B. KENT, OF NEW YORK, N. Y., ASSIGNOR, BY MESNE ASSIGNMENTS, TO
WESTERN ELECTRIC COMPANY, INCORPORATED, A CORPORATION OF NEW YORK.

LOADING-COIL AND CASE THEREFOR.

1,168,312.

Specification of Letters Patent.

Patented Jan. 18, 1916.

Application filed September 12, 1914. Serial No. 861,394.

To all whom it may concern:

Be it known that I, STANLEY B. KENT, a citizen of the United States, residing at New York, in the county of New York and State 5 of New York, have invented certain new and useful Improvements in Loading-Coils and Cases Therefor, of which the following is a full, clear, concise, and exact description.

10 This invention relates to air-gap loading coils, that is to say, coils having one or more gaps in their cores, and its object is to provide a case therefor of the best shape and of minimum dimensions consistent with the 15 maintenance of coil efficiency.

The invention has been applied, for example, to a certain type of loading coil having a toroidal core formed of semi-circular sections separated by air-gaps. There are in 20 such a coil two gaps at diametrically opposite points in the core. Loading coils constructed in this way have been found especially useful in conjunction with amplifying repeaters and telegraph instruments, 25 the air-gaps giving the coils a demagnetizing factor sufficient to reduce the residual magnetism due to strong foreign currents to a point where the telephonic transmission is not impaired.

30 Loading coils are generally inclosed in a case of cast iron, this material being desirable because cheap, substantial and weatherproof. Difficulty has been experienced, however, in the use of loading coils inclosed 35 in cast iron cases or pots, and particularly in phantom circuit coils when the windings thereof are subjected to opposing currents flowing in the side circuits. This is because of magnetic leakage creating eddy

40 current and hysteresis losses in the material of the case, thereby impairing the efficiency of the coils. The difficulty is especially present in loading coils of the type herein considered having air-gaps in their cores, 45 the reason being that there is a greater tendency to leakage of magnetic lines in such coils than there is in a closed core coil. It has been found desirable to enlarge the inclosing case for the air-gap coils in order to 50 lessen the tendency of the leakage lines to enter the case. But merely increasing the size of the case in all its dimensions does not afford a satisfactory solution of the difficulty as it greatly increases the cost of the 55 case, as well as making it unwieldy without

proportionately decreasing the energy loss in the case.

About any magnetic source, such as an electromagnet or a conductor carrying electric current, surfaces may be drawn where- 60 in the magnetic force is uniform. These are usually curved surfaces, their particular configuration depending upon the characteristics of the magnetic source. If the source, such as a loading coil, is to be inclosed with 65 magnetic material, such as the iron loading coil case, and if for a given volume inclosed by the case the minimum loss, due to energy dissipation in the inclosing material, is to be obtained, the contour of the inclosing ma- 70 terial should be such that its inner surface coincides approximately with a surface of uniform magnetic force inclosing the given volume.

This invention is based in part upon the 75 foregoing principle. To express it in another way, the invention provides a casing so shaped that the magnetic leakage lines are substantially uniformly distributed over the inner surface of the case adjacent to the 80 coil, the shape being such that the inner surface of the case has a contour graduated as to distance from the coil and being at a greater distance adjacent the air-gap than elsewhere. 85

The invention will be more clearly understood by reference to the accompanying drawings, wherein—

Figure 1 is a plan of a casing inclosing 90 three loading coils, the casing being shown with the cover removed and partly in section along the line 1—1 of Fig. 2; Fig. 2 is a side elevation with the casing in section along the line 2—2 of Fig. 1; and Fig. 3 is a fragmentary view front elevation in section along line 3—3 of Fig. 1. 95

Referring to the drawings, a casing 1 having three compartments, 2, 3 and 4 is provided for two side circuit loading coils 5 and 6, and one phantom circuit loading coil 7, respectively. The compartments are formed of the outer walls of the casing and inner partitions 8. A single cover 9 completes the inclosure for all the coils, being held to the casing by bolts 10, 10. The coils shown in the drawings are of a type having a toroidal core with two diametri- 100 cally opposite air-gaps maintained by gap spacers 11 and 12. Spacing blocks of wood are provided for holding the coils centrally 105 110

within their compartments. One of the blocks 13 rests in the bottom of the coil compartment. Four other blocks, 14, 15, 16 and 17, are arranged around the sides of 5 the coil. These blocks are of such size and shape that they suspend the loading coils farther away from the bottom and top walls of the compartments than from the side wall 18, 19. The distance of the coils from the 10 walls 20 and 21 is likewise greater than the distance from the side walls 18 and 19. The greatest distance between the coil and the casing is opposite that part of the coil which includes the air-gaps, and the least is oppo- 15 site that part of the coil which is farthest away from the air-gaps. After the coils have been placed in their compartments, the casing is filled with an insulating compound up to the line 23. An insulating partition 20 plate 24 is then placed over the coils, this partition resting upon the ledge 25 of the casing. The terminal wires 26 of the coils are then brought through bushings 27, piercing this plate and the appropriate con- 25 nections made to the outside of the casing through bushings 28. Certain of the connections between the coils are made by terminal conductors passing through bushings 30 in the inner partitions 8. The casing is finally filled up to a point 32, near the top, 30 by another layer of insulating compound and the cover bolted in place. The case may be suspended as shown on a pole 34 by means of brackets 35 and bolts 36.

35 The inner surface of each compartment, it is noted, conforms generally to a flattened ellipsoid, the long axis (A—B, Figs. 2 and 3) of which is coincident with a line ex- 40 tending through the centers of the two air- gap spacers 11, 12. The magnetic lines which escape between adjacent poles through space external to the gaps, will spread to a small extent toward and into the case. This leakage tendency is greatest 45 close to the gaps when the poles are strongest, but at these points the distance between

the core and case is greatest. On the other hand, at points farther away from the gaps, the tendency to leakage gradually diminishes and likewise the distance between the core 50 and casing gradually diminishes. The magnetic leakage lines are thus spread uniformly over a wide area of the case with a consequent reduction in the so-called "potting loss," and the case is no larger in any of its 55 dimensions than necessary to gain the required efficiency of the loading coils with- in it.

What is claimed is:

1. The combination with a toroidal load- ing coil having a magnetic core with a non- magnetic gap therein, of a case of magnetic material for said loading coil and conforming generally to the contour of the coil, said casing being elongated so as to be located at 65 a greater distance from the coil adjacent the gap than elsewhere.
2. The combination with a toroidal load- ing coil having a core of magnetic material with a non-magnetic gap, of a casing of 70 magnetic material for said loading coil, said casing having a contour coinciding approxi- mately with a surface of uniform force due to magnetic leakage from the coil.
3. The combination with a toroidal load- ing coil having a core of magnetic material with a non-magnetic gap, of a casing of 75 magnetic material for said loading coil, said casing having a contour graduated as to distance from the coil so that, for a given 80 value of hysteresis and eddy current losses in the casing due to magnetic leakage lines, the volume inclosed by the casing is sub- stantially a minimum.

In witness whereof, I hereunto subscribe 85 my name this 11th day of September, A. D. 1914.

STANLEY B. KENT.
